UNITED STATES PATENT OFFICE

2,625,500

PROTECTIVE PREPARATION AGAINST
MUSTARD GAS

Joseph N. Loehle, Baltimore, Md., assignor to the
United States of America as represented by
the Secretary of War

No Drawing. Application July 24, 1942,
Serial No. 452,196

4 Claims. (Cl. 167—63)

(Granted under Title 35, U. S. Code (1952),
sec. 266)

1

The invention described herein may be manufactured and used by or for the Government for governmental purposes, without the payment to me of any royalty thereon.

This invention relates generally to preparations adapted to protect the flesh and skin of man and beast against mustard gas, lewisite, and like chemical warfare vesicant agents.

The severe and very dangerous blistering action of mustard gas, lewisite, and like vesicants, on the flesh and skin of man and beast has long been fully realized and extensive measures and precautions have been taken to protect military personnel as completely as possible against these chemical warfare agents. In this connection, one phase of protective development has been the provision of preparations to be applied to areas of the skin and flesh exposed to vesicant agents. If possible these preparations should be applied to flesh or skin before it has been touched with vesicants. In case it is not possible to get protective preparations on the skin before it is contacted with a vesicant, they should be applied as soon as possible to the exposed area so as to prevent or at least limit the blistering action.

The object of this invention, generally stated, is to provide new and improved preparations adapted to protect the flesh and skin of man and beast against mustard gas, lewisite, and like chemical warfare vesicant agents and particularly characterized in being: easily prepared and stored; adequately stable under all conditions except extremely high abnormal temperatures; readily and easily applied to the skin; and, non-irritant and non-toxic to skin and flesh.

For a more complete understanding of the nature and scope of the invention, reference may be had to the following detailed description thereof setting forth, by way of illustration, certain specific compositions and methods of compounding the same.

It is known that vesicant agents such as mustard gas and lewisite may be converted into non-vesicant products by halogenation, and particularly by chorination. Although as a general class, N-chloro organic compounds having adequate stability against decomposition may be used in preparations for the purpose of destroying vesicants by chorination, a number of difficulties are involved in providing suitable emulsions for carrying these active compounds.

According to the present invention, excellent emulsions or bases for carrying active N-chloro organic compounds may be made comprising, a suitable solvent for the active N-chloro compound

which solvent is non-reactive therewith, such as triacetin, a mucilage, a soap, and an alkali forming ingredient such as sodium bicarbonate. In addition, an emulsion-stabilizing substance, such as a bentonite suspension, may be included with the foregoing ingredients. A preparation having the following specific composition has been found to provide one satisfactory embodiment of the invention:

	Per cent
Dichloramine-T	18.9
Triacetin	56.5
Aqueous soap mixture (about 70% soap)	3.8
Mucilago chondri	18.9
Sodium bicarbonate	1.9

The above specific preparation may be made according to the following procedure:

1. A first part is made by warming the triacetin to 50–60° C. and then adding the dichloramine-T to the solution.

2. A second part is made by measuring and mixing together the soap mixture, the mucilage, and the sodium bicarbonate.

25 3. The first part is then added to the second part with constant stirring and the mixture is expressed through an aluminum homogenizer so as to make the preparation into an emulsion. If desired the preparation may be suitably colored and scented.

30 Although the preparation having the above formulae gave adequate protection and was found to be nonirritant to human skin, it proved to have an irritating action on the skin of horses.

35 It was found however, that this formulae could be modified so as to provide an improved preparation which was not irritant either to the skin of humans or horses and other beasts. This improved preparation has the following composition:

	Per cent
Dichloramine-T	11.1
Triacetin	30.3
Aqueous soap mixture (50% soap)	4.1
Mucilago chondri	50.7
Sodium bicarbonate	2.0
Bentonite suspension (1% bentonite in water)	1.8

50 The improved preparation can be prepared according to the procedure outlined above for preparing the first-mentioned formulae. That is, a first part is made by mixing the dichloramine-T and the triacetin together. A second part is made by mixing together the remaining ingredients. Then the first part is added to the second

with constant stirring and the resulting mixture is expressed through an homogenizer. If desired, the preparation may be suitably colored and scented as desired.

From inspection of the foregoing formula it will be seen that substantial percentage ranges for the various ingredients are permissible, particularly in respect to the dichloramine-T, triacetin, mucilago, aqueous soap mixture and sodium bicarbonate.

Preparations having the following percentage ranges were found the most satisfactory:

	Per cent
Dichloramine-T	11.1-18.9
Triacetin	30.3-56.5
Aqueous soap mixture (50%-70% soap)	3.8-4.1
Mucilago chondri	18.9-50.7
Sodium bicarbonate	1.9-2.0

The preparations should preferably be packed in amber-colored bottles and stored at room temperature. Upon standing, the preparations may in certain instances separate to a slight degree after the manner of emulsions, but may be easily re-emulsified by shaking into the normal smooth, creamy texture.

Tests have shown that the active chlorine content of the preparations when stored in amber glass bottles, at room temperature, will normally remain constant with only very slight variations over a period of six weeks or more. Thus, it will be seen that the preparations are adequately stable.

Since certain changes and modifications may be made in the foregoing compositions and methods of preparing the same without departing from the scope of the invention, it is intended that all matter contained in the above description shall be given a construction as broad as is consistent with the state of the prior art.

What is claimed as new is:

1. A preparation in emulsion form adapted to protect the flesh and skin of man and beast against mustard gas, lewisite, and like vesicants, which comprises, dichloramine-T as a vesicant destroying agent, triacetin as an organic solvent for the vesicant destroying agent, mucilago chondri, an aqueous soap mixture, and sodium bicarbonate.

2. A preparation in emulsion form adapted to protect the flesh and skin of man and beast

against mustard gas, lewisite, and like vesicants, which comprises dichloramine-T, triacetin, mucilago chondri, an aqueous soap mixture, sodium bicarbonate, and bentonite suspension for stabilizing the preparation.

3. A preparation in emulsion form adapted to protect the flesh and skin of man and beast against mustard gas, lewisite, and like vesicants, which comprises substantially:

	Per cent
Dichloramine-T	18.9
Triacetin	56.5
Aqueous soap mixture (70% soap)	3.8
Mucilago chondri	18.9
Sodium bicarbonate	1.9

4. A preparation in emulsion form adapted to protect the flesh and skin of man and beast against mustard gas, lewisite, and like vesicants, which comprises substantially:

	Per cent
Dichloramine-T	11.1
Triacetin	30.3
Aqueous soap mixture (50% soap)	4.1
Mucilago chondri	50.7
Sodium bicarbonate	2.0
Bentonite suspension (1% bentonite in water)	1.8
